Primary Examiner — Jack Reickel*Assistant Examiner* — Michael A Kervin(74) *Attorney, Agent, or Firm* — Lucas & Mercanti, LLP(57) **CLAIM**

The ornamental design for a soldering iron holder, as shown and described.

DESCRIPTION

FIG. 1 is a top, front, right side perspective view of the soldering iron holder;

FIG. 2 is a top, front, left side perspective view thereof;

FIG. 3 is a top, rear right side perspective view thereof;

FIG. 4 is a top, rear, left side perspective view thereof;

FIG. 5 a front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The broken lines show portions of a soldering iron holder which forms no part of the claimed design.

1 Claim, 9 Drawing Sheets(56)
